UNITED STATES PATENT OFFICE.

JOHN N. PRINGLE, OF MILLEDGEVILLE, PENNSYLVANIA, ASSIGNOR OF ONE-HALF TO WILLIAM C. PRINGLE, OF SAME PLACE.

DESIGN FOR A BRAKE-SHOE HOLDER.

SPECIFICATION forming part of Design No. 30,202, dated February 14, 1899.

Application filed January 19, 1899. Serial No. 702,727. Term of patent 14 years.

To all whom it may concern:

Be it known that I, JOHN N. PRINGLE, a citizen of the United States, residing at Millidgeville, in the county of Mercer and State of Pennsylvania, have invented and produced a new and original Design for a Brake-Shoe Holder, of which the following is a specification.

This invention relates to a new and original design for a brake-shoe holder; and it has for its object to provide a design of this character that shall be both useful and ornamental.

The leading feature of the design resides in a rectangular block provided at one side with a pair of offstanding parallel U-shaped ears or lobes having openings therein and at the side opposite said ears or lobes with a centrally-located circular boss.

Another feature of the design resides in the rectangular block provided with the longitudinal rectangular opening piercing the same from end to end and having centrally in the opposite wide flat walls of said opening longitudinally-rounded grooves or recesses.

The minor features of the design are the rectangular block, being provided with a slightly-convexed exterior surface and exterior rounded corners, and the said longitudinal rounded grooves or recesses in the walls of the rectangular opening being of a tapering depth.

In the drawings, Figure 1 is a perspective view of a brake-shoe holder embodying the herein-described design. Fig. 2 is an end view of the same. Fig. 3 is a longitudinal sectional view on the line 3 3 of Fig. 2. Fig. 4 is a similar view on the line 4 4 of Fig. 2.

The brake-shoe holder forming the subject-matter of the present application is designed for use in connection with iron and wood brake-beams and embodies the novel configuration or design shown in the accompanying drawings.

Referring to the drawings, the numeral 1 designates the rectangular block or body of the holder, which is provided with a slightly-convexed exterior surface and with rounded corners 2. The said rectangular block 1 is further provided with a longitudinal rectangular opening 3, piercing the same from end to end and having formed centrally in the opposite wide flat walls 4 thereof the longitudinal rounded grooves or recesses 5. The longitudinal rounded grooves or recesses 5 in the wide walls of the rectangular opening 3 are located directly opposite each other and are of a tapering depth.

In addition to the features described the rectangular block or holder is further provided at one side thereof with a pair of offstanding parallel U-shaped ears 6, having circular openings 7 therein, and at the side opposite said ears 6 the body is provided with a centrally-located offset circular boss 8.

What is claimed is—

The design for a brake-shoe holder, herein shown and described.

In testimony that I claim the foregoing as my own I have hereto affixed my signature in the presence of two witnesses.

JOHN N. PRINGLE.
